Primary Examiner — Austin Murphy(74) *Attorney, Agent, or Firm* — Raymond Y. Chan; David and Raymond Patent Firm(57) **CLAIM**

The ornamental design for a stylus with illumination device, as shown and described.

DESCRIPTION

FIG. 1 is a perspective view of stylus with illumination device showing my new design.

FIG. 2 is another perspective view thereof, showing the illumination device of the stylus.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken line in the drawing is included for the purpose of illustrating environmental detail and forms no part of the claimed design.
